UNITED STATES PATENT OFFICE.

JOSEPH F. RUSSELL, OF CHICAGO, ILLINOIS.

RAIL-FASTENING DEVICE.

1,189,489.

Specification of Letters Patent.

Patented July 4, 1916.

Application filed September 25, 1915. Serial No. 52,679.

To all whom it may concern:

Be it known that I, JOSEPH F. RUSSELL, a citizen of the United States, and a resident of the city of Chicago, county of Cook, and 5 State of Illinois, have invented certain new and useful Improvements in Rail-Fastening Devices, of which the following is a specification.

This invention relates to improvements in 10 rail fastening devices and has for its object the production of a device of this character which will be of durable and economical construction, one, through the medium of which, a rail may be securely fastened in position with ease and expedition, and one 15 which will be adapted to positively prevent creeping or relative longitudinal movement of the rail engaged thereby.

Other objects will appear hereinafter. 20 With these objects in view the invention consists in the combination and arrangement of parts hereinafter described and claimed.

The invention will be best understood by reference to the accompanying drawing, 25 forming a part of this specification, and in which—

Figure 1 is a top plan view of a rail fastening device showing the same applied to a rail, a portion of the device being broken 30 away to better illustrate the construction, and Fig. 2 is a section taken on line $\alpha-\alpha$ of Fig. 1.

The preferred form of construction as 35 illustrated in the drawings comprises a rectangular metallic base plate 1 upon which the rail 2 which it is desired to fasten is adapted to be mounted. The plate 1, in use, is secured to the corresponding supporting tie by means of spikes or pins 3, 4 and 5.

40 Formed at the upper side of the base plate 1 adjacent one end thereof is a permanent jaw 6 adapted for engagement with one edge portion of the base of the rail. Mounted upon the upper side of plate 1 at the opposite end thereof is a movable jaw 7 secured in position by means of the spikes 4 and 5 which pass through elongated slots 8 formed in the rearward portion 8 of the jaw 7, the elongation of said slots permitting, of 45 course, of the desired shifting movement of the jaw. Formed integral with the jaw 7 is a forwardly projecting tenon 9 which slidably engages an elongated slot 10 formed for the reception thereof in the plate 1. 50 Said tenon, when the device is in use, is adapted to engage under the base of the rail, 55

as clearly shown in Fig. 2, so that the rail serves as a means of positively locking the jaw 7 against upward movement.

The jaw 7 is locked in operative position 60 by means of a locking member or keeper 11 which is pivotally mounted upon the upper end of a tubular post 12 which is formed integral with the plate 1, projecting upwardly therefrom. The portion 8 of jaw 7 is formed 65 with an elongated slot 12' to afford clearance for the post 12 as will be readily understood. The keeper 11 is held in position upon the post 12 by means of the pin 5 which engages in the opening in said post, 70 the head of said pin overhanging said post so as to engage against the upper side of member 11 as will be readily understood. The post 12 is of such a height as to project 75 slightly above the upper side of the member 11 so as to hold the head of pin 5 from clampingly engaging with the upper side of keeper 11, the result being that said keeper is held in position upon said post but in such a manner as to permit of free pivotal movement of the same. Said keeper is adapted 80 for engagement with a shoulder 11' which is formed upon the jaw portion 8, the arrangement being such that when said keeper is rocked into engagement with said shoulder, 85 after movement of jaw 7 into operative relation with the rail base, said jaw will be locked into operative position, being prevented from moving outwardly to releasing position. Pivotal movement of keeper 11 in one 90 direction, when said member is in locking position, is prevented by means of a lug 13 formed upon the upper side of the jaw portion 8, movement of said member in the opposite direction being prevented by a spike 95 14 adapted to be driven into operative position engaging with registering slots 15 formed in the jaw portion 8 and the plate 1. With this arrangement it will be seen that 100 when it is desired to rock the keeper 11 to inoperative position in order to release the rail, it is first required to withdraw the spike 14, whereupon said keeper will be released to permit of the desired movement of the same.

In order to insure against creeping of the rail, the bottoms of the jaws 6 and 7 are formed with projecting teeth 16 adapted for engagement with correspondingly positioned recesses 17 formed in the lateral edges of the rail base. Said teeth are of tapering form 110 and said recesses are correspondingly shaped

so as to take up any wear and insure a snug engagement between the same. With this arrangement it is of course apparent that creeping of the rail, that is relative longitudinal movement of the same, will be positively prevented.

With the construction set forth, in the fastening of a rail therein, the jaw 7 is first slid outwardly to its outer terminal movement, the base of the rail being then placed upon the plate 1 and one side of the base thereof engaged with the jaw 6, the recesses 17 in this side of the rail base (said recesses having been previously formed therein) being engaged with the corresponding teeth 16. The jaw member 7 is then slid into engagement with the opposite edge of the rail base, the teeth 16 thereof being engaged with the corresponding recesses 17. The keeper 11 is then turned to engagement with the shoulders 11' in order to lock said jaw in operative position. When the member 11 is in operative position the spike 14 is driven to position to securely hold the keeper in operative relation with the shoulders 11'. The reverse operation is of course resorted to when it is desired to release the rail from the device.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention what I claim as new and desire to secure by Letters Patent is:

1. A rail fastening comprising a base plate upon which the rail is adapted to be mounted; a permanent jaw on said plate for engagement with one edge of the base of the rail; a movable jaw coöperating with said plate for engagement with the opposite edge of the rail base; an integral projection on said plate; and a keeper pivotally mounted on said projection adapted to be turned into engagement with one edge of said movable jaw to lock the same in operative position, substantially as described.

2. A rail fastening comprising a base plate upon which the rail is adapted to be mounted; a permanent jaw on said plate for engagement with one edge of the base of the rail; a movable jaw coöperating with said

plate for engagement with the opposite edge of the rail base; an integral projection on said plate; a keeper pivotally mounted on said projection adapted to be turned into engagement with one edge of said movable jaw to lock the same in operative position, there being an opening formed through said projection; and a headed member engaging with said opening and adapted for engagement with the outer side of said keeper to hold the latter in position upon said projection, substantially as described.

3. A rail fastening comprising a base plate upon which the rail is adapted to be mounted; a permanent jaw on said plate for engagement with one edge of the base of the rail; a movable jaw mounted upon the upper side of said plate and transversely adjustable thereon into and out of engagement with the opposite edge of said rail base; an integral upwardly projecting tubular post on said plate, there being an elongated slot 80 in said movable jaw affording clearance for said post; a keeper pivotally mounted on said post adapted to be turned into engagement with one edge of said movable jaw to lock the same in operative position; and a headed pin engaging with the opening in said post and having its head overhanging the upper side of said keeper to hold the latter in position upon said post, substantially as described.

4. A rail fastening comprising a base plate upon which the rail is adapted to be mounted; a permanent jaw on said plate for engagement with one edge of the base of the rail; a movable jaw coöperating with said plate for engagement with the opposite edge of the rail base; a post on said plate; a keeper pivotally mounted on said post adapted to be turned into engagement with said movable jaw to lock the same into operative position; and means overhanging the outer end of said post for holding said keeper in position thereon, said post being slightly higher than the corresponding dimension of said keeper whereby said overhanging means 105 is prevented from clampingly engaging with the adjacent side of the keeper, substantially as described.

In testimony whereof I have signed my name to this specification in the presence of two subscribing witnesses.

JOSEPH F. RUSSELL.
